UNITED STATES PATENT OFFICE.

LEVI N. BACHAND, OF CHICAGO, ILLINOIS.

FURNITURE

993,636.

Specification of Letters Patent. Patented May 30, 1911.

Application filed June 16, 1909. Serial No. 502,540.

To all whom it may concern:

Be it known that I, LEVI N. BACHAND, citizen of the United States, residing at Chicago, in the county of Cook and State of Illinois, have invented a certain new and useful Improvement in Furniture, of which the following is a full, clear, concise, and exact description, reference being had to the accompanying drawings, forming a part of this specification.

My invention relates to furniture, and has for its object the provision of a structure which may, in one adjustment, constitute a bed, and, in another adjustment, constitute a couch.

In practicing my invention, I employ a mattress-supporting element, which desirably is formed of three panels, two outer panels and an inner panel, the outer panels being foldable at right-angles to the inner panel. A mounting is provided for the mattress-supporting element, whereby an axis of rotation is afforded, which desirably lies midway between the longitudinal edges of the mattress-supporting element, and which mounting permits the mattress-supporting element to be rotated to occupy alternative positions.

My invention has for its further object the provision of means for imparting to a metal folding bed and couch, the appearance of a couch and bed including wooden head and foot-boards in its formation.

There are many objects and advantages in the bed and couch of my invention which will be readily understood by reference to the accompanying drawings, showing the preferred embodiment of the invention, in which—

that enables the bed to be bodily rotated about a central axis. Fig. 8 is a detail illustrating a portion of the brace construction involved in the mattress-supporting element. 60 Fig. 9 is a perspective view of a bed with the mattress-supporting element unfolded, the mattress in position thereupon, and finishing hoods located over the end frames of the structure. Fig. 10 is a detail view of locking 65 mechanism that is employed to hold the mattress-supporting element in a position to which it has been rotated. Fig. 11 is a plan view of the structure illustrated in Fig. 10. Fig. 12 is a detail view illustrating the 70 mounting at one end of the mattress-sup- porting element, whereby this element may be rotated about a fixed axis. Fig. 13 is a view in the direction of arrow 13 of Fig. 7.

Like parts are indicated by similar characters of reference throughout the different figures.

The mattress-supporting element is made up of a central panel *a* extending longitudinally of the structure, and side panels *b* and 80 *c*. The central panel includes in its formation angle-irons *a*¹ *a*¹ extending transversely of the structure and mounted as hereinafter specified to have the proper distance pre- 85 served therebetween, and strip metal slats *a*² 85 united with the angle-irons *a*¹ by means of coil springs *a*³ that are attached to the ends of the said slats. The end panels each in- 90 clude angle-irons *b*¹ extending transversely of the structure and pivotally united at their 90 inner ends with the ends of the angle-irons *a*¹, as indicated most clearly in Figs. 3 and 5, where such pivotal connections *b*² are shown, the locations of the pivots *b*² being such that when the panels *b*¹ are laid horizontally and 95 the mattress-supporting element is in its nor- mal position, the inner panel will support the outer panels. The outer panel *b* *b* in- 100 cludes a side rail *d* extending longitudinally of the bed structure and the panel *c* includes 100 an outer rail *d*¹ also extending longitudi- 105 nally of the bed structure. These rails *d* *d*¹ are desirably in the form of hollow rods and are desirably anchored at their ends to the angle-irons *b*¹, as illustrated most clearly in 105 Fig. 8, where I have shown the tubular rail *d*¹ in longitudinal section and within it one arm *d*² of a right-angular brace which is secured to the rail *d*¹ by means of rivets which pass through the wall of the rail and 110 through the portion *d*² of the angle brace. The arm *d*², belonging to the same brace that

40 Figure 1 is a sectional plan view on line 1 1 of Fig. 2, of a bed constructed in accord- 45 ance with my invention. Fig. 2 is a longi- tudinal sectional view on line 2 2 of Fig. 1. Fig. 3 is a sectional view on line 3 3 of Fig. 2. Fig. 4 is a sectional view on line 4 4 of Fig. 1, with the mattress-supporting element folded, Fig. 1 showing this element un- 50 folded. Fig. 5 is a view similar to Fig. 3, with the exception that the hood covering shown in Fig. 3 is omitted in Fig. 5 and the mattress-supporting element is inverted. Fig. 6 is a sectional view illustrating a de- 55 tail of construction that will hereinafter be described. Fig. 7 is a view in sectional plan illustrating a roller rack feature of the in- 60 vention which enters into the construction,

includes the arm d^2 , is disposed at right-angles to the arm d^2 and is riveted to the angle d^1 as illustrated. By this construction a very firm union is afforded between the 5 longitudinal rails d d^1 and the transverse rails b^1 of the outer panels b c . These outer panels also include strip metal slats a^5 , united with the end rails b^1 by means of coil springs a^4 . Each transverse rail a^1 of the 10 central panel is provided with a pivotal mounting located midway between the ends thereof. Fig. 12 is a detail view showing one of these pivotal mountings which is located at the right-hand end of the bed structure as 15 viewed in Figs. 1 and 2, the pivotal mounting for the companion transverse rail a^1 being similar in construction to the one illustrated in Fig. 12, but symmetrically arranged with respect to the pivotal mounting 20 shown in Fig. 12, as would be expected. These pivotal mountings preferably include stationary stub-shafts e that project inwardly from and are carried by the end standard frames f , each frame being mounted upon casters g , whereby the bed structure 25 supported by these casters may be readily shifted. Distance pieces g^1 intervene between the frame structure f and the inner heads of the stub-shafts or bolts e , whereby 30 the middle panel may clear the end frames f and whereby the mattress-supporting element composed of the panels a b c , may be held in a fixed plane of rotation with respect to the frames f . When the panels are 35 unfolded to occupy the positions illustrated in Figs. 1, 2 and 3, the mattress h may be supported in position. The pivotal mountings for the mattress-supporting element permit such element to be rotated to occupy an inverted position, and when this inversion in 40 the position of the mattress-supporting element is to occur, straps i are secured at their ends to buttons or pins k , as illustrated most clearly in Figs. 2 and 9, whereby the mattress 45 is strapped in position. Before the mattress-supporting element is inverted, the side panels b c thereof are turned at right-angles to the middle panel, whereafter the strap l permanently attached at one end to 50 the longitudinal rail d , is separably attached to the button m provided upon the longitudinal rail d , whereby the angular relation of the side panels b c with respect to the middle panel is maintained, and whereby the 55 mattress-supporting element, together with the mattress support, may be inverted, the mattress being held in position by means of the straps i . To assure a fixed plane of rotation for the mattress-supporting element, 60 I provide circular tracks n whose track surfaces are parallel with respect to the plane of rotation of the mattress-supporting element and which track surfaces are engaged by track rollers o mounted to rotate upon 65 brackets p that extend outwardly from the

transverse rails a^1 , the axis of rotation of the rollers o being at right-angles to the axis of rotation of the mattress-supporting element, this latter axis being substantially fixed with respect to the middle panel, the 70 entire arrangement that is being described permitting the mattress-supporting element to rotate and confining the mattress-supporting element in its rotation to a plane which is substantially fixed with respect to the 75 standard frames f and not requiring the bodily withdrawal of the mattress supporting element from and toward its mounting to change it from one kind of furniture to another. The tracks n are desirably formed 80 of angle-irons that are formed in circular shapes, additional angle-irons p^1 being united with the aforesaid angle-irons to house the track and the rollers o rolling thereupon, to protect the manipulator of the 85 bed from injury, and, further, to stiffen the structure. The angle-iron structure p^1 at each end of the bed structure is in the form of a rectangle, as illustrated in Fig. 4, the vertical sides of the rectangle being riveted 90 to the caster-supported frames f , as indicated most clearly in Fig. 7, the tops of the frames f being cut away in the lines of circular travel of the rollers o and the brackets p supporting said rollers, all as indicated 95 most clearly in Fig. 7. In order that the circular track n may be further braced, the vertical side members of each frame p^1 are continued downwardly below said frames p^1 , the extended portions of the frames p^1 upon 100 one side of the bed structure being united by distance-preserving members q that are formed by angle-irons, as illustrated most clearly in Fig. 4, and being united by rods r that pass through the channel portions of 105 the distance-preserving members, as indicated most clearly in Figs. 2, 4 and 6.

In order that the swinging mattress-supporting element may be held in either of its alternative positions, I provide in each 110 transverse rail section a^1 , two slots s (see Fig. 5) that are equi-distant from the axis of rotation of the mattress-supporting element, and I mount upon the top rail of each 115 caster-supported frame f , a catch t (see Figs. 7 and 11 in particular) that may be swung into and out of engagement with a juxtaposed slot s , respectively to hold the mattress-supporting element in position or to free the same, to permit it to be rotated, each catch t being for the purpose fixed with respect to a vertical stub-shaft u journaled in the top rail of the caster-supported frame f and provided with an operating handle v . The catches t , when engaging slots s , prevent rotation of the mattress-supporting element in either direction. I, however, prefer to employ additional means at each end 120 of the bed structure for taking part in holding the mattress support, which desirably 125

resides in such a construction as is shown in Fig. 13, provided at each end of the bed and located on the opposite side of the axis of rotation of the mattress-supporting element 5 with respect to the fastening devices *t*. These supporting devices each include a holding-bar *w* pivoted at *x*, and a mounting *y* carried by the caster-supported frame *f*, the mountings *y* carrying pins *z* upon the 10 inner sides of the pivots *x*, to prevent the inner ends of the catches *w* from being depressed; the outer ends *w*¹ of the catches *w* engaging structural portions of the supports *f* for a similar purpose. The catches *w* thus limit the bed to rotation in one direction, the catches rising when engaged by the 15 rotating mattress-supporting element to permit of such rotation, and falling back to normal to take part in holding the mattress-supporting element in the position to which it has been rotated.

For the sake of appearance, I provide decorative or finishing hoods *A*, which slip over the track structures *n* and the end portions of the caster-supported frames *f*, the hoods being open on their inner faces to permit the roller-supporting brackets *p* to extend therein.

When the mattress-supporting element is caused to occupy a position in which the mattress is inverted, the parts occupy the position well illustrated in Fig. 5, in which position the bed structure is converted into a couch structure.

While I have herein shown and particularly described the preferred embodiment of my invention, I do not wish to be limited to the precise details of construction shown, as changes may readily be made in the embodiment of my invention illustrated without departing from the spirit thereof.

Having thus described my invention, I claim as new and desire to secure by Letters Patent the following:

1. An article of furniture including a mattress-supporting element divided into three hinge-connected panels extending longitudinally of the structure, means for holding the outer panels in angular relation to the central panel, a mounting for the mattress-supporting element permitting it to be inverted, said mounting defining an axis of rotation for the mattress-supporting element which extends longitudinally of the structure substantially midway between the longitudinal sides of the central panel of said mattress-supporting element, circular perpendicularly disposed tracks, rollers carried by the mattress-supporting element moving upon said tracks as the mattress-supporting element is shifted in position, and finishing hoods inclosing the frame-work at the head and foot of the bed structure.

2. An article of furniture including a

mattress-supporting element divided into three hinge-connected panels extending longitudinally of the structure, means for holding the outer panels in angular relation to the central panel, a mounting for the mattress-supporting element permitting it to be inverted, circular perpendicularly disposed tracks, rollers carried by the mattress-supporting element moving upon said tracks as the mattress-supporting element is shifted in position, and finishing hoods inclosing the frame-work at the head and foot of the bed structure.

3. An article of furniture including a mattress-supporting element divided into three hinge-connected panels extending longitudinally of the structure, a mounting for the mattress-supporting element permitting it to be inverted, circular perpendicularly disposed tracks, rollers carried by the mattress-supporting element moving upon said tracks as the mattress-supporting element is shifted in position, and finishing hoods inclosing the frame-work at the head and foot of the bed structure.

4. An article of furniture including a mattress-supporting element divided into three hinge-connected panels extending longitudinally of the structure, means for holding the outer panels in angular relation to the central panel, a mounting for the mattress-supporting element permitting it to be inverted, said mounting defining an axis of rotation for the mattress-supporting element and in substantially fixed relation with the central panel and which extends longitudinally of the structure substantially midway between the longitudinal sides of the central panel of said mattress-supporting element, circular perpendicularly disposed tracks, and rollers carried by the mattress-supporting element moving upon said tracks as the mattress-supporting element is shifted in position.

5. An article of furniture including a mattress-supporting element divided into three hinge-connected panels extending longitudinally of the structure, means for holding the outer panels in angular relation to the central panel, a mounting for the mattress-supporting element permitting it to be inverted, circular perpendicularly disposed tracks affording an axis of rotation substantially fixed with respect to the central panel, and rollers carried by the mattress-supporting element moving upon said tracks as the mattress-supporting element is shifted in position.

6. An article of furniture including a mattress-supporting element divided into three hinge-connected panels extending longitudinally of the structure, a mounting for the mattress-supporting element permitting it to be inverted and affording an axis of rotation substantially fixed with respect to the panel

directly carried by the mounting, circular perpendicularly disposed tracks, and rollers carried by the mattress-supporting element moving upon said tracks as the mattress-supporting element is shifted in position.

7. An article of furniture including a mattress-supporting element divided into three hinge-connected panels extending longitudinally of the structure, means for holding the outer panels in angular relation to the central panel, and a mounting for the mattress-supporting element permitting it to be inverted, said mounting defining an axis of rotation for the mattress-supporting element which extends longitudinally of the structure substantially midway between the longitudinal sides of the central panel of said mattress-supporting element and which is substantially fixed with respect to the central panel, and finishing hoods inclosing the frame-work at the head and foot of the bed structure.
- 10 8. An article of furniture including a mattress-supporting element divided into three hinge-connected panels extending longitudinally of the structure, means for holding the outer panels in angular relation to the central panel, and a mounting for the mattress-supporting element permitting it to be inverted, said mounting defining an axis of rotation for the mattress-supporting element which extends longitudinally of the structure substantially midway between the longitudinal sides of the central panel of said mattress-supporting element and which is substantially fixed with respect to the central panel.

- 15 9. An article of furniture including a mattress-supporting element divided into three hinge-connected panels extending longitudinally of the structure, means for holding the outer panels in angular relation to the central panel, and a mounting for the mattress-supporting element permitting it to be inverted and affording an axis of rotation substantially fixed with respect to the panel directly carried by the mounting.
- 20 10. An article of furniture including a mattress-supporting element divided into three hinge-connected panels extending longitudinally of the structure, and a mounting for the mattress-supporting element permitting it to be inverted and affording an axis of rotation substantially fixed with respect to the panel directly carried by the mounting.

- 25 11. An article of furniture including a mattress-supporting element divided into three hinge-connected panels extending longitudinally of the structure, means for holding the outer panels in angular relation to the central panel, and a mounting for the mattress-supporting element permitting it to be inverted and affording an axis of rotation substantially fixed with respect to the panel directly carried by the mounting, and finishing hoods inclosing the frame-work at the head and foot of the bed structure.
- 30 12. An article of furniture including a mattress-supporting element divided into three hinge-connected panels extending longitudinally of the structure, a mounting for the mattress-supporting element permitting it to be inverted and affording an axis of rotation substantially fixed with respect to the panel directly carried by the mounting, and finishing hoods inclosing the frame-work at the head and foot of the bed structure.

35 13. An article of furniture including a mattress-supporting element divided into three hinge-connected panels extending longitudinally of the structure, means for holding the outer panels in angular relation to the central panel, a mounting for the mattress-supporting element permitting it to be inverted, said mounting defining an axis of rotation for the mattress-supporting element which extends longitudinally of the structure substantially midway between the longitudinal sides of the central panel of said mattress-supporting element and which is substantially fixed with respect to the central panel, and finishing hoods inclosing the frame-work at the head and foot of the bed structure.

40 14. An article of furniture including a mattress-supporting element divided into three hinge-connected panels extending longitudinally of the structure, means for holding the outer panels in angular relation to the central panel, a mounting for the mattress-supporting element permitting it to be inverted and affording an axis of rotation substantially fixed with respect to the panel directly carried by the mounting, and finishing hoods inclosing the frame-work at the head and foot of the bed structure.

15 15. An article of furniture including a mattress-supporting element divided into three hinge-connected panels extending longitudinally of the structure, a mounting for the mattress-supporting element permitting it to be inverted and affording an axis of rotation substantially fixed with respect to the panel directly carried by the mounting, and finishing hoods inclosing the frame-work at the head and foot of the bed structure.

20 In witness whereof, I hereunto subscribe my name this 7th day of June A. D., 1909.

LEVI N. BACHAND.
